UNITED STATES PATENT OFFICE.

GEORGE B. STEWART, OF PITTSBURGH, PENNSYLVANIA.

NOZZLE FOR VACUUM-CLEANERS.

1,054,052.

Specification of Letters Patent. Patented Feb. 25, 1913.

Application filed August 30, 1912. Serial No. 717,949.

To all whom it may concern:

Be it known that I, GEORGE B. STEWART, a citizen of the United States, residing at Pittsburgh, in the county of Allegheny and State of Pennsylvania, have invented a new and useful Nozzle for Vacuum-Cleaners, of which the following is a specification.

The present invention relates to improvements in nozzles for vacuum cleaners, the present structure being especially designed for use in cleaning exchange boards in telephone exchanges, the primary object of the invention being the provision of an exchange board engaging member or mouth piece carried resiliently and in co-active relation to the inlet end of a nozzle, said mouth-piece being normally held away from the nozzle so that the same may be positioned upon the exchange board before the nozzle is placed into active relation thereto.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the nozzle and attachment in normal position, the exchange board engaging portion being shown partly in section. Fig. 2 is a similar view with the nozzle in active relation to the exchange board engaging portion or member. Fig. 3 is a plan view of the exchange board engaging member.

Referring to the drawings, the numeral 1 designates the nozzle head which is adapted to have the end 2 connected to a suction hose (not shown), and carried by the head at diametrically opposite points are the two arms 3 carrying each a guiding sleeve 4.

Mounted for sliding movement in the sleeves 4 are the two rods 5 each one of which is provided with the limiting head 5' and has its other end connected to the lug 6 of the exchange board engaging member or mouth-piece 7. This is preferably made of an insulating material so as to avoid any short circuiting when used in connection with the exchange board.

The mouth-piece 7 is provided with a plurality of inlet apertures 8 and in order to

provide a means to prevent injury to the exchange board and at the same time to provide a chamber upon the exchange board engaging side of the mouth-piece 7, a rim 9 of felt or rubber is carried as shown.

In order to hold the mouth-piece 7 away from the nozzle 1, as shown in Fig. 1, the coiled springs 10 are disposed upon the rods 5 and engage at one end the sleeves 4 while at the other end the lugs 6.

When it is desired to operate the present device, the mouth-piece is presented to the exchange board with the rim 9 thereagainst and by a slight pressure upon the nozzle 1, the two springs 10 are compressed as shown in Fig. 2, until the nozzle 1 engages the mouth-piece 7, thus confining the suction action to the perforated portion of the mouth piece 7 and thus only acting upon the exchange board when the nozzle 1 is pressed against the mouth piece. By this means the mouth-piece is first positioned upon the exchange board and no suction action is permitted to take place until the nozzle 1 is in the position as shown in Fig. 2. It is also evident that by reason of the springs 10 the release of the nozzle 1 will permit of an automatic adjustment of the members from the position as shown in Fig. 2 to that shown in Fig. 1, thus automatically relieving the mouth-piece 7 of any suction action when the tool is being removed or released.

What is claimed is:

1. In a tool for vacuum cleaners, the combination of a nozzle having an inlet and an outlet, a mouth piece mounted for movement to and from the inlet of said nozzle, and resilient means to normally hold the mouth-piece away from said inlet.

2. In a tool for vacuum cleaners, the combination of a nozzle having an inlet and an outlet, a perforated mouth-piece, and means carried by the nozzle and mouth-piece for resiliently connecting the mouth-piece to the nozzle for movement to and from the inlet thereof.

3. In a tool for vacuum cleaners, the combination of a nozzle having an inlet and an outlet, a plurality of guiding arms carried by said nozzle, a mouth-piece, a plurality of rods slidably mounted in said arms and connected to and carrying the mouth-piece, and a spring mounted upon each rod for resiliently holding the mouth-piece away from the inlet end of the nozzle.

4. A tool for vacuum cleaners, including a nozzle, a pair of arms carried thereby, a mouth-piece, a pair of rods carried by said mouth-piece and slidably mounted in said arms, and a spring mounted upon each rod for yieldably holding the mouth-piece out of engagement with the nozzle.

In testimony that I claim the foregoing as my own, I have hereto affixed my signature in the presence of two witnesses.

GEORGE B. STEWART.
